UNITED STATES PATENT OFFICE.

SAMUEL E. W. HAINES, OF BERKELEY, CALIFORNIA.

ROAD SIGN OR SIGNAL.

Application filed October 24, 1923. Serial No. 670,611.

My invention relates to improvements in road signs or signals and more particularly to that class of signals consisting of light reflectors adapted for arrangement at road intersections, crossings or dangerous curves, to warn approaching motorists of danger.

The object of my invention is to construct a signal or reflector of mirrored glass, preferably of a cardinal color, adapted to receive the light rays from the headlights of approaching automobiles and reflect them in such a manner that the driver will be warned at a considerable distance of a dangerous curve or crossing as the case may be.

Another object is to produce such a sign or reflector that may be of any design or size and placed in such relation to curves or turns of the highway that it will be discernable at least a half mile away, that is in case of a substantially straight highway leading up to said reflector; and the reflected rays becoming stronger and more brilliant as the machine nears said reflector.

Other objects and advantages and the features of construction of the invention will appear in the subjoined description of the accompanying sheet of drawings, in which:

Fig. 1 is a diagrammatic view illustrating the method of placing a pair of reflectors at a bend or curve in the roadway in accordance with the principles of my invention; said reflectors being placed slightly within the apex formed by the outer lines of said roadway and each facing one arm of the roadway.

Fig. 2 is an elevation of an embodiment of my invention shown in the form of an arrow.

Fig. 3 is an elevation of another embodiment showing a "curve sign" instead of the arrow.

Fig. 4 is a vertical section showing a method of supporting the reflector sections, taken upon line 4—4 of Fig. 2.

Fig. 5 is an enlarged transverse section showing the flutations or corrugations of the reflector, taken upon line 5—5 of Fig. 4.

As disclosed in the accompanying drawings the signs or reflectors may be mounted in any suitable frame or support or at the corners of buildings and a suitable distance from the ground to properly receive and reflect the rays of light and distribute them somewhat lat-

erally and not above or below the range of vision.

The reflector is preferably constructed of fluted glass, with the flutations extending vertically when the reflector is in position upon the support. Said flutations receive rays of light and project them in a substantially fan-shaped beam with relation to the flutations of the reflector and laterally of said flutations.

The mirror or reflector may be any shape or design and preferably constructed in sections, so that any one section may be removed and replaced if broken and may consist of an ornamental design of corrugated or fluted glass. The flutations or corrugations in the glass extending vertically thereof to produce a slight prismatic effect upon the incident rays to widen out the reflected beam; so that it may be visible from any part of the road within the line of approach.

Referring to Figs. 2, 4 and 5. (1) in a general way designates the reflector preferably consisting of several sections of mirrored glass (2), cut to imitate any desired configuration, such as, an arrow; said sections (2) are held in place by a frame (3) of light metallic material. Said frame consists of a back support (4) having outwardly extending portions (5) and retaining flanges (6). This frame (3) may be nailed or otherwise secured to a board (7) which in turn is bolted to the upright or post (8) by bolts (9).

The sections (2) are silvered on their inner faces as indicated at (10) and the flutations or corrugations (11) are formed on their outer or both faces and extend vertically from the lower to the top edges of said sections. These flutations are molded or rolled in the glass and when considered transversely the contour thereof forms a continuous series of concavo-convex surfaces.

I have shown and described the reflector (1) as of mirrored glass, but it is to be understood that said reflector may be constructed of a highly polished metal such as aluminum or brass having the flutations extending vertically thereof in the same manner.

The metal construction would necessarily be provided with a colored glass front to produce desired colored or cardinal diffusions.

Having thus illustrated and described my

invention in its preferred form, I wish it understood that the same may be modified as practice suggests. Therefore, the patent protection that I desire is all of that which comes within the spirit and scope of the invention as claimed.

I claim:

In a signal of the class described, a plate

of transparent material having a plane reflecting back surface and a fluted front surface, the signal being adapted to disperse therefrom a beam of light fan-shaped in a substantially horizontal plane when the plate is positioned vertically with the flutes thereof vertical and at a desired point in the road.

SAMUEL E. W. HAINES.
